UNITED STATES PATENT OFFICE.

GEORGE HENRY ELWELL, OF CLEVELAND, OHIO, ASSIGNOR TO CARR FASTENER COMPANY, OF CAMBRIDGE, MASSACHUSETTS, A CORPORATION OF MAINE.

SNAP FASTENER.

Application filed October 31, 1923. Serial No. 671,965.

My invention relates to improvements in snap fasteners and more particularly to stud and socket fasteners separable only by a relative tipping movement in a certain direction.

The object of my invention is to provide a novel rigid stud member that may be used in combination with a socket member employing a resilient element such as a split 10 spring ring.

With this and other objects in view, as will more fully hereinafter appear, the invention consists in certain features of novel construction and arrangement of parts hereinafter described, illustrated in the accompanying drawing and particularly pointed out wherein patentable novelty is claimed for certain features of the device, it being understood that within the scope of what hereinafter thus is claimed various changes in form, proportion, size and minor details of the construction can be made without departing from the spirit or modifying any of the advantages of the invention.

25 The following is the description of an embodiment of my invention, reference being had to the accompanying drawing, in which Figure 1 is a side view of a stud; Figure 2 is a top view of the same stud with shoulder 30 shown in dotted line; Figure 3 is a side view of interlocked fastener members mounted on fabric, the socket member being partly shown in cross-section; Figure 4 is a bottom view of socket member showing, partly in dotted line, the normal position of split ring; and Figure 5 is a view similar to the 35 next preceding figure excepting that the split ring is shown in shifting position as when members are interlocked.

40 Referring more particularly to the drawing, in which similar parts are similarly numbered, the stud member has a base 1, neck 2 and head 3, as best shown in Figures 1 and 3, and proper attaching means 4, as shown in Figure 3. The head 3 and the neck 2 are so formed that the head 3 presents a rearwardly facing abrupt shoulder 5 nearly encompassing the stud member, or on three sides thereof as shown in dotted line in Figure 2. At the fourth side of the stud the neck portion 2 is extended laterally with relation to the head of the stud as clearly shown in Figs. 1 and 2, so that the head 3 presents to that portion of the neck 55 2 a rounded shoulder 6, as best shown in

Figure 1. The neck 2 of the stud is, therefore, made egg-shaped in cross-section for the purpose of providing the three-sided locking engagement with the socket, this egg-shaped cross-section being best illustrated in dotted lines, Fig. 2. While I have shown in Figure 3 a socket member of a particular construction yet that member may be of any other construction employing any resilient means adapted to interlockingly engage a stud member of the type above described. For the purpose of description I have preferred to show in Figures 3, 4, and 5, a socket member employing a split ring 7, formed from spring wire, as the resilient element.

In operation, the socket member is passed onto the stud member and as head 3 enters the stud passage it engages the inner surface of ring 7 and spreads that ring sufficiently to allow the head 3 to pass through the ring 7 which immediately thereafter retracts as soon as it is permitted to engage neck 2. Ring 7, nearly throughout its entire circumference, is thus lodged behind the abrupt shoulder 5 and is thereby positively locked against direct withdrawal and against tipping of the socket member in any direction emanating from any portion of the abrupt shoulder 5. In assuming the locked position, as shown in Figure 3, the ring 7 is shifted from its normal position, as shown in Figure 4, to the position shown in Figure 5. To separate the fastener members the socket member must be tipped so that the ring 7 is first forced over the rounded shoulder 6 of the stud head 3 and thus spreading ring 7 until it slips from under and behind the abrupt shoulder 5 and releases the socket member from its interlocked engagement with the stud member. 75 85 90 95 00 05

What I claim is:—

1. A snap fastener comprising, in combination, a stud and a socket adapted to be engaged by direct axial movement of one toward the other, said socket presenting a stud-receiving aperture intersected by resilient stud engaging means, a cooperating stud having head and neck portions, said stud-engaging means adapted to engage said neck when said socket and stud are engaged, an abrupt shoulder between the neck and said head at three sides of the stud for interlocking engagement with said resilient stud-engaging means to prevent separation of the 100
165
170

- fastener when stress is exerted at any one or all of the sides where said abrupt shoulder is provided, and a laterally extended portion of said neck provided at the fourth side of the stud to provide a smoothly rounded surface at said fourth side whereby said resilient stud-engaging means may be disengaged from the stud by a pull adjacent said laterally extending portion.
- 10 2. A snap fastener comprising, in combination, a stud and a socket adapted to be engaged by direct axial movement of one toward the other, said socket presenting a stud-receiving aperture intersected by resilient 15 stud-engaging means, a cooperating stud having a base, a head and a neck between said base and said head, said neck being substantially egg-shaped in cross-section to provide an abrupt shoulder between the head and neck at three sides for interlocking engagement with said resilient means when said stud and socket are engaged, and to provide at the fourth side a wall portion

substantially even with the head to permit the resilient means to be guided over the head when a pull is exerted at said fourth side.

3. A snap fastener comprising, in combination, a stud and a socket adapted to be engaged by direct axial movement of one toward the other, said socket presenting a stud-receiving aperture intersected by a ring type resilient stud-engaging spring, a co-operating stud having a base, a head and a neck between said base and said head, said neck being offset toward one side relative to said head to provide an abrupt shoulder between the head and neck at three sides for interlocking engagement with said resilient means when said stud and socket are engaged, and to provide at the fourth side a wall portion substantially even with the head to permit the resilient means to be guided over the head when a pull is exerted at said fourth side.

GEORGE HENRY ELWELL.
